Patented July 4, 1922.

FIG. 1.

FIG. 2.

Harry C. Adams Inventor

UNITED STATES PATENT OFFICE.

HARRY C. ADAM, OF ST. LOUIS, MISSOURI.

DESIGN FOR PRINCIPAL CENTRAL BODY OF A LIGHTING FIXTURE.

61,146.

Specification for Design.

Patented July 4, 1922.

Application filed September 3, 1921. Serial No. 498,548. Term of patent 14 years.

To all whom it may concern:

Be it known that I, HARRY C. ADAM, a citizen of the United States, residing at St. Louis, Missouri, have invented a certain new, original, and ornamental Design for the Principal Central Body of a Lighting Fixture, of which the following is a specification, reference being had to the accompanying drawings, forming a part thereof.

Fig. 1 of the drawings, is a perspective view,

Fig. 2, is a bottom plan view of my new ornamental design for a lighting-fixture body.

I claim:

The ornamental design for the principal central body of a lighting fixture, as shown.

HARRY C. ADAM.
